United States Patent Office

Des. 211,345
Patented June 11, 1968

211,345

DENTAL CONSOLE

Richard A. Slouka, Carpentersville, Ill., assignor to American Hospital Supply Corporation, Evanston,
Ill., a corporation of Illinois

Filed May 24, 1967, Ser. No. 7,249

Term of patent 14 years

(Cl. D24—1)

FIG. 3

FIG. 1 is a front elevational view of the dental console design;

FIG. 2 is a side elevational view;

FIG. 3 is an elevational view of the side opposite that shown in FIG. 2;

FIG. 4 is a rear elevational view; and

FIG. 5 is a top plan view.

The broken lines are shown for illustrative purposes only.

I claim:

The ornamental design for a dental console, substantially as shown and described.
